UNITED STATES PATENT OFFICE

105,528

DESIGN FOR A DOMESTIC CLOTHES DRIER

Joseph W. Jensen, Chicago, Ill., assignor to Electric Household Utilities Corporation, Chicago, Ill., a corporation of Illinois

Application June 14, 1937, Serial No. 69,838

Term of patent 14 years

To all whom it may concern:

Be it known that I, Joseph W. Jensen, a citizen of the United States, residing at Chicago, in the county of Cook and State of Illinois, have invented a new, original, and ornamental Design for a Domestic Clothes Drier, of which the following is a specification, reference being had to the accompanying drawing, forming a part thereof.

In the drawing—

The figure is a perspective view of a domestic clothes drier, embodying my new design.

I claim:

The ornamental design for a domestic clothes drier, as shown.

JOSEPH W. JENSEN.
